[57] CLAIM

The ornamental design for a banking machine terminal or the like, substantially as shown and described.

DESCRIPTION

FIG. 1 is a front elevational view of a banking machine terminal or the like showing our new design; FIG. 2 is a front perspective view thereof; FIG. 3 is a rear elevational view thereof; and, FIG. 4 is a left side elevational view thereof, the side opposite being substantially a mirror image.

1

FIG 3

Fig. 4
